UNITED STATES PATENT OFFICE.

WILLIAM H. GARLAND, OF KANSAS CITY, MISSOURI, ASSIGNOR OF ONE-HALF TO RAYMOND M. HAVENS, OF KANSAS CITY, MISSOURI.

LOOSE-LEAF POST BINDER.

No. 882,059.

Specification of Letters Patent. Patented March 17, 1908.

Application filed October 26, 1906. Serial No. 340,769.

To all whom it may concern:

Be it known that I, WILLIAM H. GARLAND, a citizen of the United States, residing at Kansas City, in the county of Jackson, son and State of Missouri, have invented certain new and useful Improvements in Loose-Leaf Post Binders, of which the following is a specification.

This invention relates to loose leaf post binders and has for its object to produce a device of this character which operates efficiently and reliably and is of simple, strong, durable and cheap construction.

A further object is to produce a binder of the character named in which the upper member of the cover cannot be accidentally locked with or unlocked from the posts carried by the lower member.

To these ends the invention consists in certain novel and peculiar features of construction and organization as hereinafter described and claimed; and in order that it may be fully understood reference is to be had to the accompanying drawing, in which—

25 Figure 1, is a section on the line I—I of Fig. 2. Fig. 2, is a section on line II—II of Fig. 1. Fig. 3, is a section on line III—III of Fig. 1.

In the said drawing 1 indicates the lower member of the cover and 2 the cloth or equivalent jacket thereof, said jacket being prolonged at one end to form the loop 3, for the metal bar 4 upon which the posts 5 are erected, which posts are preferably of the 35 sectional type, though their particular construction is immaterial.

6 indicates the upper member of the cover and 7 the jacket therefor of cloth or equivalent material, said jacket being prolonged at one end to provide the loop 8 to receive and hold a tubular bar 9, which bar is preferably formed of sheet metal bent to approximately the cross sectional configuration shown in Figs. 2 and 3, and said bar is provided in its upper and lower walls with holes 10 of sufficient size to pass freely over the caps or heads 11 of the posts 5, it being understood that the perforated sheets 12, will be clamped between the upper and lower members of the binder, their perforations being of sufficient size to pass freely over the caps or heads of the posts. 13 indicates a pair of similar bearing blocks which fit together and are disposed by preference 55 within the tubular bar and about a quarter

of an inch from its left hand end though its particular location is of course immaterial, and said blocks are provided with mating channels or grooves 14, for a purpose which hereinafter appears.

60 The blocks are secured together and to the tubular bar by rivets 15, and similar rivets 16 extend through the tubular bar to form guides for a wedge clamp 17, the same preferably consisting of a bar bent to form the 65 straight body portion 18 and the substantially parallel arms 19, which converge with respect to the back wall of the tubular bar and toward the left hand end of the same so as to find a bearing thereagainst, the rear end 70 of the right-hand wedge arm being bent rearwardly as at 20 to bear against the rear wall of the tubular bar and prevent said wedge arm from material yielding under certain conditions. The front end of the left-hand 75 wedge arm 19 is bent forwardly as at 21 and provided with a screw-seat to receive the threaded end of screw 22, having its non-threaded portion journaled in the opening formed by the grooves 14 of blocks 13, longitudinal movement of the screw being prevented by the rigid collars 24 thereon engaging opposite sides of the bearing blocks. By 80 preference the screw has a squared head as at 25 so that before it can be turned, it must 85 be engaged by a key as at 26 or equivalent device inserted through a hole 27 in the left-hand end of the loop 8 of jacket 7.

In practice it is necessary if an additional sheet or sheets is to be placed on the binder 90 or it is desired to remove one or more of the sheets thereof, to turn the screw so as to cause the wedge clamp 17 to slide to the right and thereby withdraw from engagement with the posts. The upper member of 95 the cover can then be lifted off the posts as will be readily understood. After replacing said member upon the posts it can be clamped tightly at the desired point of adjustment by turning the screw in the direction opposite to 100 that in which it was first turned, this reverse action of the screw causing the wedge clamp to slide to the left and its arms 19 to wedge tightly against and between the back wall of the tubular bar and the posts, there being by 105 preference sufficient resiliency in the wedge arms to insure a positive clamping action on both posts at all times. The screw is turned by means of the key 26 or other suitable device. It is therefore proof against manipu- 110

lation by anyone unless provided with a key or equivalent tool and because of the threaded relation between the screw and wedge clamp the latter is locked against accidental movement in either direction.

From the above description it will be apparent that I have produced a loose leaf post binder possessing the features of advantage enumerated as desirable in the statement of 10 the object of the invention and which may be modified in various particulars without departing from the spirit and scope of the appended claims.

Having thus described the invention what 15 I claim as new and desire to secure by Letters Patent, is:—

1. In a loose leaf binder, a tubular bar, blocks secured in one end and provided with mating grooves, a screw journaled in said 20 blocks and provided with collars at opposite sides of the latter, a slideable clamp comprising a pair of approximately parallel wedge arms converging with and bearing at their front ends against a wall of the tubular bar, 25 one of the wedges having at its rear end a brace arm also bearing against said wall and the other wedge a front arm provided with a screw seat engaged by said screw.

2. In a loose leaf binder, a tubular bar, 30 blocks secured in one end and provided with mating grooves, a screw journaled in said blocks and provided with collars at opposite sides of the latter, a slideable clamp comprising a pair of approximately parallel wedge 35 arms converging with and bearing at their front ends against a wall of the tubular bar, one of the wedges having at its rear end a brace arm also bearing against said wall and the other a front arm provided with a screw 40 seat engaged by said screw, and guiding means for the slideable clamp intermediate of its wedge arms.

3. In a loose leaf binder, a lower cover member provided with a plurality of upwardly projecting posts, an upper cover member provided with a tubular bar having alined openings in its upper and lower walls to slidily engage said posts, blocks secured within and near one end of said tubular bar, 45 a screw journaled in said blocks, means to prevent longitudinal movement of said screw when turned, and a slideable clamp extending longitudinally within the tubular bar and provided with a pair of substantially 50 parallel wedge arms contiguous to said open-

ings and between said posts and the rear wall of the tubular bar, and provided with a screw seat engaging said screw and adapted when the latter is turned in one direction to act as wedges between the back wall of said tubular bar and said posts and when turned in the opposite direction to withdraw from engagement with the latter.

4. In a loose leaf binder, a lower cover member provided with a plurality of upwardly projecting posts, an upper cover member provided with a tubular bar having alined openings in its upper and lower walls to slidily engage said posts, blocks secured within and near one end of said tubular bar, 60 a screw journaled in said blocks, means to prevent longitudinal movement of said screw when turned, a slideable clamp extending longitudinally within the tubular bar and provided with a pair of substantially parallel wedge 65 arms contiguous to said openings and between said posts and the rear wall of the tubular bar and provided with a screw-seat engaging said screw and adapted when the latter is turned in one direction to act as 70 wedges between the back wall of said tubular bar and said posts and when turned in the opposite direction to withdraw from engagement with the latter, and a key detachably secured upon the screw for turning the same 75 in either of said directions.

5. In a loose leaf binder, a lower member having upwardly projecting posts, an upper member having a bar fitting on said posts to slide up and down thereon, a clamp carried 80 by said bar and consisting of a body portion extending longitudinally of the bar and substantially parallel oblique resilient arms at opposite ends of the body portion and arranged between the posts and a part of the 85 bar, one of said arms terminating in a brace arm also bearing against said part of the bar and the other in an oppositely projecting arm provided with a thread seat extending longitudinally of the bar, and a screw arranged longitudinally of and bearing a 90 swivel relation to the bar and having its threaded portion engaging said thread seat.

In testimony whereof I affix my signature, in the presence of two witnesses.

WILLIAM H. GARLAND.
